[57] CLAIM

The ornamental design for a stackable disposable beverage container, as shown and described.

DESCRIPTION

FIG. 1 is a front elevational view of the stackable disposable beverage container showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is an enlarged cross-sectional view taken vertically through the mid-plane of the stackable disposable beverage container at line 7—7 of FIG. 5.

The word “LOGO”, depicted by means of broken lines in FIGS 1 through 4, has been shown for illustrative purposes only forms no part of the claimed design.
